UNITED STATES PATENT OFFICE.

JOHN MRACEK, OF CHICAGO, ILLINOIS.

HOT-WATER HEATER.

No. 920,982.

Specification of Letters Patent.

Patented May 11, 1909.

Application filed May 14, 1908. Serial No. 432,850.

To all whom it may concern:

Be it known that I, JOHN MRACEK, a citizen of the United States, residing at Chicago, in the county of Cook and State of Illinois, 5 have invented certain new and useful Improvements in Hot-Water Heaters, of which the following is a specification.

This invention relates to heating appliances for rooms, apartments, and the like, 10 having reference more particularly to that type wherein the heating effect is secured by the circulation of hot water through suitable heat-radiating devices.

The main object of the invention is to provide 15 an independent and self-contained heating apparatus employing a gaseous fuel, by which I mean an apparatus wherein each radiator is equipped with its own means for heating and regulating the temperature of 20 the water circulating therein, independent of the conditions that may exist in other radiators employed in the same room or building.

My invention, in one approved mechanical form in which the same may be embodied, is 25 illustrated in the accompanying drawing, wherein the figure is a side elevation of a portion of an ordinary hot water radiator with water-heating and gas-controlling attachment applied thereto, the latter appearing 30 partly in vertical section.

Referring to the drawing, 1 designates an end portion of an ordinary hot water radiator, the upper and lower limbs of which are connected for the circulation of water by a 35 pipe herein shown as comprising upper and lower horizontal sections 2 and 3, respectively, and an intermediate vertical section 4 connected to the horizontal section by upper and lower elbow couplings 2^a and 3^a, respectively. In the vertical section 4 of this pipe is interposed a somewhat enlarged section herein shown as a hollow tapered member 4^a, wide at its bottom and narrow at its top and freely communicating at both ends with the 45 upper and lower sections of the pipe 4, as shown. Surrounding the enlarged section 4^a of the pipe 4 is a drum 5 containing an annular water chamber 6 formed by and between the inner and outer walls of the drum, this latter being connected and communicating 50 freely with the upper and lower ends of the tapered section 4^a by a series of pipes 7 and 8, respectively. Surmounting the drum 5 and surrounding the upper section of the 55 pipe 4 is a cone-shaped hood 9, which latter,

as also the tapered or cone-shaped section 4^a, is preferably and as herein shown, corrugated.

Directly below the lower or wide end of the tapered pipe section 4^a, and surrounding the lower section of the pipe 4, is an annular gas burner 10, provided with the usual series 60 of jet apertures 11 in its upper side. Tapping this burner ring laterally is a gas-supply pipe 12 in which is interposed an ordinary 65 valve-cock 13, the stem of which is bent at right angles and extended alongside the supply-pipe, as shown at 14. A coiled spring 15 connected at one end to the arm 14 of the valve and at its other end to a bracket 16 70 supported by the supply-pipe 12, or to any other convenient point of attachment, normally tends to open the valve 13.

Surmounted on the upper pipe section 2, or any other part of the radiator, is an expansion tank 17 herein shown as supported upon a central pipe 18 through which the interior of the tank communicates freely with the pipe section 2 and the water in the radiator. In this tank is secured a diaphragm 19, 75 to which is connected by clamping plates 20 and 21 a valve-actuating rod 22, the lower end of which passes through an aperture in the valve arm 14, being adjustably connected to the latter by a nut 23 engaging the 80 threaded lower end of the rod. A filling tube 24 for the radiator communicates with the expansion tank 17 below the diaphragm 19, and an indicator tube 25 and thermometer 26 serve, respectively, to indicate the height, 85 and temperature of the water in the radiator.

27 indicates a small pipe tapping the gas-supply pipe 12 on the supply side of the valve 13 and extending to a point adjacent to the upper edge of the burner, and constituting 90 a pilot light.

In operation, the radiator, including the end pipe attachment to which the burner is applied, having been filled with water, the gas is ignited at the burner 10, which rapidly 100 heats the water in the superposed pipe sections 4^a and 4, as likewise the water in the annular drum 5. This at once institutes and, so long as the water remains heated, maintains a circulation of water between the upper and lower parts of the radiator through the described pipe connections at the end of the latter. As the water becomes heated, it rises through the pipe 18 into the expansion 105 tank 17, and as it exceeds in temperature the 110

predetermined desired point, it raises the dia-
phragm 19 and, through the latter and the
valve-rod 22, lifts the valve-arm 14 against
the action of spring 15 and partially or
5 wholly cuts off the supply of gas to the
burner, thus either reducing or extinguishing
the heating flame. By adjusting the nut 23,
the supply of gas to the burner may be re-
duced or cut off when a greater or less tem-
10 perature has been reached in the water cir-
culating through the radiator, since the ex-
pansion and contraction of the water are pro-
portional to its rise and fall of temperature.
In the normal operation of the device, the
15 burner will be automatically maintained,
through control of the gas supply therefor, at
such a heat as suffices to maintain at a uni-
form point the desired temperature in the ra-
diator. If, however, through variations in
20 gas pressure or from any other cause, this
temperature is exceeded, the supply thereof
is at once further acted upon to further re-
duce or entirely cut off the gas to the burner.
In the latter event, the rapid reduction in
25 temperature of the water which follows soon
permits the valve to be re-opened, where-
upon the pilot light at once reestablishes the
heating flame at the burner.

The drum 5 with its annular water cham-
30 ber contributes materially to the efficiency
of the burner in heating the water by adding
a considerable surface area that is exposed
on one side to the water in the system and
on the other side to the heating effects of the
35 products of combustion. By reason of the
fact that the cooling water enters the cone-
shaped section of the circulation pipe cen-
trally of its lower wide end, and of the fur-
ther fact that the latter is freely connected
40 both at top and bottom to the upper and
lower ends of the annular water chamber
by the series of radially disposed pipes 7 and
8, a substantial equilibrium of the water in
the conical and annular chambers is main-
45 tained at all times, the contracted or nar-
rowed upper end of the conical chamber, in
association with the free communication be-
tween the lower ends of the two chambers,
also forcing the water into contact with a
50 large area of heating surface, whereby local
circulation within the water-heating device
itself is avoided. The hood 9 also confines
and directs the hot gases rising from the
drum 5 to and upon the upper pipe section
55 4, thus securing additional heating effect
upon the water in said pipe section and con-
tributing to the economical and efficient utili-
zation of the heat yielded by the burner.

I. claim:

60 1. A heating appliance for rooms, apart-
ments and the like, comprising a radiator
adapted for water circulation and having a
circulation pipe connecting the upper and
lower portions thereof, the vertical portion
65 of said circulation pipe having interposed

therein an enlarged conical section coaxially
disposed with reference to said vertical por-
tion of the circulation pipe with its wide end
or base lowermost, a gas burner directly be-
neath the base of said conical section, a drum 70
having an annular water chamber surround-
ing and substantially co-extensive longitudi-
nally with said conical section, and with
the latter forming an annular flue for the
heated products of combustion from the 75
burner, a plurality of radially disposed pipes
forming a communication between the upper
ends of said conical section and drum, and a
plurality of similar pipes forming a 80
communication between the lower ends of said
conical section and drum, substantially
as described.

2. A heating appliance for rooms, apart-
ments and the like, comprising, a radiator
adapted for water circulation and having a 85
circulation pipe connecting the upper and
lower portions thereof, the vertical portion
of said circulation pipe having interposed
therein an enlarged conical section coaxially
disposed with reference to said vertical por- 90
tion of the circulation pipe with its wide end
or base lowermost, a gas burner directly be-
neath the base of said conical section, a
drum having an annular water chamber sur-
rounding and substantially co-extensive 95
longitudinally with said conical section, and
with the latter forming an annular flue for
the heated products of combustion from the
burner, a plurality of radially disposed pipes
forming a communication between the upper 100
ends of said conical section and drum, a
plurality of similar pipes forming a communica-
tion between the lower ends of said conical
section and drum, and a hood surmounting
said drum and surrounding the vertical por- 105
tion of said circulation pipe above said coni-
cal section, substantially as described.

3. A heating appliance for rooms, apart-
ments and the like, comprising a radiator
adapted for water circulation and having a 110
circulation pipe connecting the upper and
lower portions thereof, the vertical portion
of said circulation pipe having interposed
therein an enlarged conical section coaxially
disposed with reference to said vertical por- 115
tion of the circulation pipe with its wide end
or base lowermost, a gas burner directly be-
neath the base of said conical section, a drum
having an annular water chamber surround-
ing and substantially co-extensive longitudi- 120
nally with said conical section, and with the
latter forming an annular flue for the heated
products of combustion from the burner, a
plurality of radially disposed pipes forming
a communication between the upper ends of 125
said conical section and drum, a plurality of
similar pipes forming a communication be-
tween the lower ends of said conical section
and drum, a hood surmounting said drum
and surrounding the vertical portion of said 130

circulation pipe above said conical section, a fuel supply-pipe for said burner, a valve in said pipe, and means whereby the position of said valve is automatically controlled by the temperature of the water in said radiator, substantially as described.

In testimony that I claim the foregoing

as my invention, I have hereunto subscribed my name in the presence of two witnesses.

JOHN MRACEK.
